TOGGLE PLIERS

John Olson, Detroit, Mich.

Application July 22, 1940, Serial No. 346,795

12 Claims. (Cl. 81—46)

This invention relates to pliers and particularly pliers actuatable by a toggle mechanism.

An object of the invention is to adapt the jaws of a pair of pliers to be opened or closed by merely varying the point at which pressure is applied by a hand gripping the pliers, so that the other hand of a person using the tool may be entirely free to manipulate work.

Another object is to adapt either end of one handle of a pair of pliers to rock to or from the other handle and to provide for opening or closing the plier jaws accordingly as pressure is applied to one or the other end of the rocking handle.

A further object is to provide for actuation of the jaws of pliers through a pair of toggle links adapted to lock the jaws in engagement with work.

These and various other objects the invention attains by the construction hereinafter described, and illustrated in the accompanying drawings, wherein:

Fig. 1 is a side elevational view of the pliers, with their jaws open.

Fig. 2 is a similar view with the jaws closed.

Fig. 3 is a top plan view of the tool.

Fig. 4 is a cross sectional view taken upon the line 4—4 of Fig. 2.

Fig. 5 is a fragmentary section taken on the line 5—5 of Fig. 2, showing particularly the lower jaw.

Fig. 6 is a side elevational view of the pliers in a modified form.

Fig. 7 is a cross section taken on the line 7—7 of Fig. 6.

In these views, the reference characters 1 and 2 designate the paired elongated handles of my improved pliers, each preferably formed of sheet metal bent to a U or channel cross section, the mid portion of the handle 2 being integrally formed with a pair of spaced, opposed lugs 3 projecting into the channel of the handle 1 and terminally pivoted on the latter by a rivet 4 or the like. Rigidly and integrally projecting from the handle 1 and preferably aligned therewith is a jaw 5 conforming to the U cross section of said handle, and a companion jaw 6 is pivoted by a rivet or the like 7 on a support 8 transversely and integrally projecting from the handle 1 at its juncture with the jaw 5. The support 8 is hollow, comprising spaced parallel portions similarly extending from the sides of the handle 1 and jointly forming a wall 9 at the front of said support. The free end portion of said support is forwardly bent to receive the pivot rivet 7. The

jaw 6 is formed of standard bar material, its major transverse axis being in the plane jointly established by the paired jaws, except as regards the front portion of said jaw, the bar having a ninety degree twist to render the major axis of its front portion transverse to said plane.

Housed within the hollow support 8 is a pair of toggle links 10 and 11 forming an actuating connection for the jaw 6, said links when aligned being substantially transverse to the jaws. The link 10 is dual, engaging at each side of the rear end of the jaw 6 and being pivoted to the latter by a pin 12. The link 11 which is preferably single is at one end connected to the link 10 by a pin 12a and has its other end pivoted on a rivet or the like 13 disposed at the juncture of the handle 1, jaw 5, and support 8. A link bar 14 forms a swinging actuating connection from the handle 2 to the toggle links, the rear end of said bar extending into the channel of said handle, and engaging a rivet 15 at the base of the lugs 3, and the front end of said bar being pivoted to the pin 12a.

At their forward ends, the jaws 5 and 6 carry work clamps which may be constructed to suit the particular purpose of the pliers. The clamps illustrated are formed by bolts 16 engaged in oversized openings in the jaws and each rigidly secured to its jaw by a pair of lock nuts 17. Said clamps project toward each other a distance regulable by the lock nuts, and their adjacent ends are enlarged to form work-engaging heads 18 of any desired shape. Preferably the free end of the jaw 5 is so conformed to the inner lock nut 17 associated with such jaw as to restrain such nut from rotation.

The modification illustrated by Fig. 6, conforms to the preceding description as regards the handles 1' and 2', the lugs 3', the jaw 6', the support 8', toggle links 10' and 11', link bar 14', and clamping elements 16'. In place of the non-pivotal jaw 5, however, the jaw 6' is duplicated, the handle 1' having a slight forward extension 20 beyond the support 8' to pivotally mount the second jaw 6', and the toggle link 11' being pivoted to the rear end of said second jaw. In this construction, both toggle links 10' and 11' are dual and the pin 21 interconnecting said links has projecting ends guided in channels 22 formed by the opposed walls of the support 8' and extending parallel to the handle 1'.

In either form of the described tool, the jaws may be closed or opened, accordingly as the forward or rearward end portion of the handle 2 or 2' is pressed toward the handle 1 or 1'. Thus by

merely shifting the hand gripping the tool a few inches forwardly or back, the response of the jaws to an applied gripping force may be reversed. Also, without moving the hand, the position of the handle 2 or 2' may be reversed by transferring gripping stress from front to rear fingers or vice versa. This adds largely to utility of the tool, since one hand of a workman using the same may be constantly free to manipulate the work.

A further desirable feature of the tool is the fact that the toggle links are adapted, in closing the jaws on work, to swing slightly beyond a "dead center" position, as clearly appears in Fig. 2, so as to effect a locking of the jaws in engagement with the work. Movement of said links beyond "dead center" is of course slight, being limited by engagement of the front end of the bar 14 with the wall 9. Opening travel of the jaws 6 or 6' is limited by inclined upper portion of the wall 9.

An important distinction is to be noted between my improved gripping tool and those lacking a locking effect. In absence of a locking action, the work is freed on relief of the muscular effort applied to maintain gripping action of the jaws. In the tool now disclosed, upon snapping of the toggle links beyond their dead center position as illustrated by Fig. 2, there is set up a powerful resistance to separation of the jaws. Release of the jaws involves the application of a force adequate to shift the toggle links past dead center. Therefore, the handle leverage requisite for release of the jaws must be substantially equal to that provided for closing the jaws.

Limitation of opening travel of the jaws is vital in the disclosed construction since in absence of such limitation, the pin 12 might be shifted downwardly across the dead center line established jointly by the pin 12a and rivet 1, thus reversing the intended control exercised by the handle on the jaw 6.

Said pliers have numerous uses and are particularly suited for production jobs, in which a certain operation requires constant repetition, one adjustment of the work clamps serving for all such operations. The pliers are further well suited to use as a C clamp and for holding parts in intimate contact during welding or other operations.

The invention is presented as including all such modifications and changes as come within the scope of the following claims.

What I claim is:

1. A pair of pliers comprising a pair of elongated coacting handles, a pair of spaced coacting jaws mounted on one of said handles, the mounting of at least one of said jaws being pivotal, means pivoting the mid portion of the other handle on the jaw-mounting handle, a pair of toggle links interconnecting the jaws and effective to close or open the jaws accordingly as said links are shifted to or from alignment, and a link bar forming a swinging actuating connection from the mid portion of the pivotal handle to the juncture of the toggle links, whereby the jaws are opened or closed accordingly as one or the other end of the pivotal handle is rocked toward the companion handle.

2. A pair of pliers as set forth in claim 1, one of said jaws being directly mounted on the jaw-mounting handle, and such handle having a substantially transverse projecting support terminally pivotally mounting the other jaw, said sup-

port coacting with the toggle links to limit their divergency at one side of their aligned position.

3. A pair of pliers as set forth in claim 1, the rocking handle having an integral projection 5 from its mid portion terminally pivoted on the jaw-mounting handle, said link bar engaging the rocking handle at the base of said projection.

4. A pair of pliers as set forth in claim 1, one of said jaws being directly mounted on the jaw-10 mounting handle, and such handle having a substantially transverse, hollow projecting support, housing said toggle links and terminally pivotally mounting the other jaw.

5. A pair of pliers comprising a pair of elongated coacting handles, a jaw support projecting rigidly and substantially transversely from the front end of one of said handles, means pivoting the mid portion of the other handle on the mid portion of the handle carrying the jaw support, 15 a pair of spaced coacting jaws pivoted respectively on the free end of said jaw support and on the front end of the handle carrying said support, a pair of pivotally joined toggle links forming an actuating connection between the rear ends of the jaws, and a link bar forming a swinging actuating connection from the mid portion of the pivotal handle to the juncture of the toggle links.

6. A pair of pliers comprising coacting jaws, a 30 pair of handles, an actuating connection from the handles to the jaws, means effective on said connection for locking the jaws in closed position responsive to their actuation to such position, and means pivoting one of said handles substan-

35 tially at its mid portion to rock at either end to and from the other handle, said pivoted handle being adapted to apply substantially the same leverage to said connection when actuated at either end, and said connection opening or closing the jaws according as one or the other end of said pivoted handle is rocked toward the other handle.

7. A pair of pliers as set forth in claim 6, said actuating connection comprising a pair of toggle 45 links, and said locking means taking effect on said links.

8. A work holding tool comprising a pair of coacting jaws, a pair of elongated handles, pivot means mounting one of said handles at its mid 50 portion to rock on the companion handle, and an actuating connection from said mid portion to one of the jaws, effective to open or close the jaws according to the direction of rocking of the rocking handle, the handles having gripping portions 55 at both sides of said pivot means, whereby the jaws may be opened or closed accordingly as the handles are jointly gripped at one or the other side of the pivot means.

9. A work holding tool comprising a pair of 60 elongated handles, a pair of coacting jaws pivotally mounted on one of said handles, a pair of toggle links forming an actuating connection between said jaws, means pivotally mounting one of said handles at its mid portion to rock on the 65 companion handle, and an actuating connection from the mid portion of said rocking handle to said links effective to open or close the jaws according to the direction of rocking of the rocking handle, the handles having gripping portions 70 at both sides of said pivot means, whereby the jaws may be opened or closed accordingly as the handles are jointly gripped at one or the other side of the pivot means.

10. A work holding tool comprising a pair of 75 coacting jaws, a pair of elongated coacting han-

dles, a substantially transverse projection on one of said handles, means pivoting one of said jaws on said projection for movement to adapt the jaws for opening and closing travel, said projection having a portion forming a stop, engageable by and limiting opening movement of said pivotal jaw, means pivoting one of said handles upon the other, and an actuating connection from said pivotal handle to said pivotal jaw.

11. A work holding tool comprising a pair of coacting jaws, a pair of elongated coacting handles for actuating said jaws, a support rigidly projecting from one of said handles and having two stop portions, means pivoting one of said jaws on said support for coaction with the other jaw and for further coaction with one of said stop portions to limit opening travel of said pivoted jaw, means pivoting one of said handles upon the other, and an actuating connection

5 from said pivotal handle to said pivotal jaw, engageable with the other of said stop portions to effect locking of the jaws in their closed position.

12. A work holding tool comprising a pair of elongated coacting handles, a pair of gripping jaws pivoted on the forward portion of one of said handles in opposed coacting relation, means pivoting the mid portion of the other handle on an opposed portion of the jaw-mounting handle, a pair of pivotally joined toggle links forming an actuating connection between the rear ends of the jaws, a swinging actuating connection from the mid portion of the pivotal handle to the juncture of the toggle links, and coacting means upon the jaw-mounting handle and at the juncture of the toggle links for rectilinearly guiding the joined ends of the links in a forward and back travel.
